UNITED STATES PATENT OFFICE.

ANDREW J. SANFORD, OF NEWARK, OHIO.

DESIGN FOR A LIGHT-SHADE.

40,283.

Specification for Design.

Patented Oct. 5, 1909.

Application filed August 12, 1909. Serial No. 512,616. Term of patent 14 years.

To all whom it may concern:

Be it known that I, ANDREW J. SANFORD, a citizen of the United States, residing at Newark, county of Licking, and State of Ohio, have invented a new, original, and ornamental Design for Light-Shades, of which the following is a specification, reference being had to the accompanying drawing, forming a part thereof.

In the drawings Figure 1 is a perspective view of a glass shade showing my new design; and Fig. 2 is a bottom plan view thereof.

The leading features of my design comprise a body portion of oblong form with rounded ends and surface decorations of vertically extending prisms; and two tops of circular form.

I claim:

The ornamental design for a light shade, as shown and described.

ANDREW J. SANFORD.
